UNITED STATES PATENT OFFICE

EDWARD C. BYRNE AND ALFRED J. KLINGEL, OF SOUTH BEND, INDIANA

OVERSHOE FOR USE IN SPORTS

Application filed December 6, 1930. Serial No. 500,514.

The invention relates to overshoes for use in sports, and has for its object to provide light weight, low cut overshoes having spiked soles, which may be readily slipped over and removed from a regular pair of shoes, said overshoes tightly fitting over regular shoes to convert them into spiked shoes and thus replace comparatively expensive spiked sport shoes.

10 A further object is to provide an overshoe of this character which is formed of rubber whereby the sole thereof will not be destructive to a playing field or course; the upper of said overshoe being highly elastic and 15 of a construction to permit the overshoe to be worn over shoes of varying sizes and lasts, within limits, whereby overshoes made in two or three different sizes only will suffice to fit all sizes and shapes of shoes, and thus 20 greatly reduce the number of sizes necessary to be carried by a dealer to meet the requirements of the trade.

A further object is to provide a rubber overshoe of this character in which a layer of leather forms a part of the sole thereof to provide means to which the shanks of spikes may be clinched to securely hold said spikes to said overshoe.

With the above and other objects in view, 30 the invention resides in the combination and arrangement of parts as hereinafter set forth, shown in the drawings, described and claimed, it being understood that changes in the precise embodiment of the invention may 35 be made within the scope of what is claimed without departing from the spirit of the invention.

In the drawings:

Figure 1 is a side view of our overshoe 40 as worn over a regular shoe.

Figure 2 is a longitudinal vertical sectional view of our improved overshoe taken on line 2-2 of Figure 3.

Figure 3 is a top plan view of our improved 45 overshoe illustrating in dotted lines the manner in which the upper thereof may be stretched to fit shoes of varying sizes and shapes.

Figure 4 is a fragmentary vertical sectional 50 view of our overshoe which illustrates the

manner in which the upper thereof may be stretched.

Referring to the drawings, which illustrate the preferred embodiment of the invention, the numeral 10 designates the upper 55 of the overshoe, and the numeral 12 the sole thereof. The upper 10 is preferably formed of thin, highly elastic, gum rubber which is adapted to constrictively engage the edges of the soles and the lower portion of the upper of the shoe to hold the overshoe thereon, said upper comprising a narrow front portion 14 and a wide rear portion 16 adapted to fit over the heel of the shoe. The upper 10 is preferably vulcanized to the rubber outsole 18 at the marginal edges thereof, said outsole being formed of a heavier and tougher rubber than the upper.

Mounted on the inner side of the outsole 18 are a leather inner sole 20, and a leather 22 70 at the heel thereof, said leathers 20 and 22 being preferably formed of a single layer of sole leather. The outsole and leathers 20 and 22 are preferably adhesively secured together in face contact, but the outer margins 75 of the outsole engaging the leathers 20 and 22 have no connection therewith, for purposes to be hereinafter set forth. A suitable insole 24, preferably of buckram or gum rubber, is then adhesively secured to the leathers 20 80 and 22, and to the outsole 18 at the shank or instep thereof.

Spikes or cleats 26 are carried by the sole 12 and project from the bottom thereof. The cleats 26 may be of any desired type and are 85 preferably provided with a large circular flange or shoulder 28 which engages the outer surface of the outsole. The shanks 30 of the cleats extend through the rubber outsole 18 and the leathers 20 or 22, the end 32 of each shank being clinched to the leather. The buckram insole 24 then covers the clinched ends 32 of the cleats, and any clinched end projecting above the surface 90 of the leather can work into the buckram whereby protuberances on the insole are eliminated.

It will thus be seen that a spiked overshoe is provided which is of light weight, and which may be easily carried in a grip or golf 95

bag and slipped over a regular, comfortable pair of shoes when starting to play a game, thus eliminating a change to uncomfortable and ill fitting expensive spiked shoes. The 5 upper, being highly elastic, may be stretched to constrictively engage shoes of various sizes, and the outer margin of the outsole 18, which is not vulcanized to the leathers 20 and 22 and is therefore free to move relative thereto, may be distorted or bent as shown in dotted lines in Figure 4 to facilitate the wearing of the overshoe on shoes of substantially larger size. The overshoe is flexible at the shank where its sole is 15 formed only of the rubber outsole and buckram insole, and it may therefore be bent double whereby it requires only a minimum of space when carried or stored. The leathers 20 and 22 provide means for securely anchoring the cleats to the overshoe, and the outsole 18 constrictively engages the shanks of the cleats to further support them and render the sole of the overshoe waterproof. The weight of the overshoe is reduced to a 25 minimum consistent with a construction having the purposes and advantages described. The insole, which is formed of buckram, gum rubber or the like, engages and clings to the sole of the shoe on which the overshoe is 30 worn, and, in combination with the upper, holds said shoe against movement relative thereto, so that the overshoe becomes a substantially unitary part of the shoe on which it is worn from the standpoint of function 35 because the shoe cannot slide about in the overshoe.

It is to be understood that various changes in the specific construction of the overshoe may be made. Thus it is obvious that the 40 leathers 20 and 22 may be replaced by metal plates, such as aluminum or other light weight metal, which will serve to securely carry and support the shanks of the cleats in proper position. Also, the shape and 45 material of the upper may be changed if desired.

The invention having been set forth, what is claimed as new and useful is:

1. An overshoe comprising an unlined upper formed of elastic rubber, a flexible outsole, an adhesive insole, substantially rigid members interposed between said insole and outsole at the sole and heel portions of the overshoe, said outsole having its edges rolled 50 upwardly around the edges of said rigid members and insole and joined to said upper above said insole, the rolled edges of said outsole being extensible away from the edges of said rigid member and insole upon flexing of said upper to fit over shoes of various sizes.

2. An overshoe comprising an unlined upper formed of elastic rubber, a rubber outsole, an adhesive insole, adapted to prevent 55 sliding of a shoe sole relative thereto, leath-

ers interposed between said insole and outsole at the sole and heel portions of the overshoe, the edges of said outsole being joined to said upper above said insole and being extensible away from the edges of said insole and leathers upon flexing of said upper to fit over shoes of various sizes, and cleats projecting from said outsole and having their shanks secured to said leathers.

In testimony whereof we affix our signatures.

EDWARD C. BYRNE.
ALFRED J. KLINGEL.
